UNITED STATES PATENT OFFICE.

GUSTAVE E. FRANQUIST, OF NEW YORK, N. Y.

CARBURETER.

No. 840,204.

Specification of Letters Patent.

Patented Jan. 1, 1907.

Application filed August 11, 1905. Serial No. 273,719.

To all whom it may concern:

Be it known that I, GUSTAVE E. FRANQUIST, a citizen of the United States, residing at the city of New York, in the borough of 5 Manhattan and State of New York, have invented certain new and useful Improvements in Carbureters, of which the following is a full, clear, and exact description.

My invention relates to carbureters for hydrocarbon-engines, and more particularly to engines of motor-vehicles, motor-boats, and like apparatus in which a widely-varying control of the engine is obtained by the manipulation of a single lever or other simple combination of parts.

In this class of devices it is desirable to operate the engine at a very slow speed at certain times, just sufficient to maintain its rotation. When in use, the engine should be 20 controllable to suit all of the varied conditions of speed and grade of road, as well as different atmospheric conditions due to variations in heat or cold or humidity.

It is the object of my invention to provide 25 a carbureter to satisfy all the requirements which arise in practice and to further provide a device which shall be simple and easy to construct, efficient in operation, and having a minimum number of parts.

With these and other objects in view my invention consists in the construction, combination, location, and arrangement of parts, all as will be more fully hereinafter set forth, as shown in the accompanying drawings, and 35 finally particularly pointed out in the appended claims.

Figure 1 is a side view, partly in section, of a carbureter embodying the principles of my invention; and Fig. 2 is a sectional view on the broken line 2 2 of Fig. 1.

It will be understood that a hydrocarbon-engine receives air which is initially heated from a convenient apparatus, generally the usual cylinder-jackets, and is afterward 45 passed over a supply of gasoline or other hydrocarbon by which an explosive mixture is generated. When the engine has arrived at its running speed, it is advantageous in practice to supply a certain quantity of pure cool 50 air for a purpose and in a special way which will later more fully appear. In the use of my invention I accomplish all necessary functions by the motion of a single operating part, which is controlled by a regulating- 55 gear within reach of the operator on the car.

Referring now to the drawings and to the various views and references-signs appearing thereon, in which like parts are designated by the same-reference signs wherever they occur, 1 designates the float feed-chamber of a carbureter, and 2-indicates, broadly, the regulating and air admitting and mixing chamber on the carbureter. The float feed-chamber, which may be made in any convenient or desired way, forms no part of the present invention. It is merely essential to provide a device at this point which shall maintain a supply of volatile hydrocarbon fluid in an aspirator pipe or nozzle, over which the air may be led. 7 indicates such pipe or nozzle, and I have arranged chamber 2 in such a way as to support and hold this part in proper relation. In the form of my invention shown the chamber 2 is provided with cavities 3 and 4, which are separated by a web or dia- 75 phragm 5.

6 indicates a tubular extension of the cavity 4, which projects into the cavity 3 and preferably occupies a central position therein. The flaring extension 6 has a portion 6^a, which is of a comparatively small diameter, and a second portion 6^b, which flares or enlarges, so as to increase the diameter of the tubular extension to the point where it enters the chamber or cavity 4. Guided and supported by the walls of the tubular extension 6 I have arranged the nozzle 7, above referred to, which is also supported at the outer casing of the chamber in such way that the orifice of the nozzle is located approximately at the center of the tubular extension 6. For this purpose the nozzle may be formed with a screw-threaded portion 8, having a slotted head 8', which screws into a part of the outer casing, so that the nozzle is adjustable therein. 95

9 indicates a screw-plug which I arrange at a point opposite to the nozzle 7, so that the latter is accessible for cleaning, for repairs, or any other purpose. 100

10 indicates a plug having screw-threads 11 thereon which can be screwed into the walls of the chamber 2 at a point diametrically opposite from the nozzle 7, the plug passing through a wall of the tubular extension 6 for this purpose. 105

It is to be understood that the cavity 3 has ports X, which are in communication with a source of hot-air supply—such, for example, as a chamber surrounding the jacket of the 110

engine. I have omitted the showing of these ports from the drawings in order to avoid confusing the illustration of the remaining parts; but it is to be understood that they are located in any convenient way on the side walls of the chamber.

12 indicates a cap by which the cavity 3 is closed at its outer end.

The web or diaphragm 5 above referred to is formed with a valve-seat 13, and co-operating with this valve-seat I arrange a piston-valve 14, guided by the walls of the chamber.

2. In practice I arrange a guiding-sleeve 15, having a screw-threaded portion 16 thereon, which enters a correspondingly-threaded aperture 17 in the chamber 2, so as to be adjustable with relation to such chamber.

18 indicates a locking-nut which is screwed upon the threaded portion 16 of the guiding-sleeve 15, so as to firmly hold said guiding-sleeve in any position to which it has been adjusted. The sleeve 15 is also formed with a hexagonal portion 19 in the preferred form of my invention, so as to permit a convenient adjustment of the sleeve.

20 denotes the valve-stem guided by the sleeve 15, and I have shown a spiral spring 21 surrounding this stem and arranged to normally spring-press the valve 14 against its seat 13.

The valve 14 not only constitutes a means for closing the passage from the float-feed chamber to the cylinder-inlets, but it has additional functions, and I provide a number of specially-arranged ports by which these additional purposes are accomplished.

22 indicates a port upon valve 14, and 22' indicates a corresponding port or opening in the cylinder-casing. These ports are so arranged as to be out of register with one another when the valve 14 is fully closed, but pass into alignment after a certain movement of the valve.

23 and 23' indicate additional ports which are generally similar to the ports 22 and 22', except that I arrange these ports a greater distance out of register with one another than ports 22 and 22', so that greater movement of the valve is necessary to bring them into alignment.

24 and 24' indicate still further ports upon the valve and casing which are arranged to move into alignment when the valve is opened widely.

55. The ports above mentioned are of different sizes, so that as the valve moves outward an increasing quantity of cool air is admitted, and in practice I arrange the valves so that the admission of cool air exactly corresponds to the needs of the engine for that particular position of the valve.

It will be understood that the amount of cool air required is not necessarily proportional to the movement of the valve, and in practice the varied conditions necessitate

particular mixtures of cool air and air from the carburetor-chamber in a manner which will later more fully appear.

25 indicates a notch which I form in the lower edge of the valve 14, so that a small passage is provided from the carburetor to the engine when the valve is closed. The purpose of this notch is to enable an engine to be run at a very slow speed while the car is standing still in order to avoid the necessity of "cranking" when it is desired to again run the car.

The operation is as follows: A supply of gasoline or other hydrocarbon is admitted to the float-feed-chamber 1 and from thence by the usual float feed-valve mechanism in a manner which is well understood is fed into the supply pipe or nozzle 7. At this time the engine may be running at slow speed or may be manually turned in the operation of cranking; but in any case a vacuum is created in the cylinders and air is sucked from the source of hot-air supply into the chamber 3 and through the tubular extension 6. By virtue of the comparatively small diameter of the tubular extension 6, the air rushes past the supply pipe or nozzle 7 with considerable rapidity and sucks or aspirates a quantity of gasoline from said pipe, which is generally proportional to the quantity of air.

At this time all of the ports 22, 23, and 24 are closed and the heated and carbureted air from the tubular extension 6 is of a richness and character suitable to the needs of the engine at this time. Should it now be desired to increase the speed of the engine, the valve 14 is drawn outward, so that the air mixture is not throttled in its path to the cylinders, but it is sucked through the carburetor freely with a velocity proportional to the speed of the engine. Under these circumstances the speed of the engine rapidly increases and the velocity of the air-current in the tubular extension 6 becomes proportionally increased, and since an aspirator works more efficiently for high velocities a greater amount of gasoline is absorbed than is desirable. Accordingly the ports 22 and 22' come into register and admit a quantity of cool pure air into the mixture which is just sufficient to dilute it properly. An additional factor of this cool air is to provide a more condensed mixture, or, in other words, a greater weight of gas per stroke of the engine with proportionately greater power. As the valve 14 is opened more and more widely the engine takes on further increased speeds and the new conditions necessitate greater and greater amounts of cool air, which is appropriately admitted for each position of the registering ports 23, 23' and 24, 24'.

Under variations of weather and temperature it sometimes becomes necessary to vary the proportions of cool air admitted to the mixture. This is conveniently done in my

device by releasing the lock-nut 18 and adjusting the guiding-sleeves 15 in and out of the casing 2. I prefer to make this adjustment by successively screwing the guiding-sleeve 15 exactly one turn in or out of the casing 2, so that successive adjustments are provided according to the screw-pitch; but, if desired, the guiding-sleeve may be turned circumferentially through a slight angle, so as to partially throttle all of the ports 22, 23, and 24.

When the car is stopped, the valve 14 is closed upon its seat, at which time the opening 25 is just sufficient to keep the engine slowly rotating.

It will be seen that I provide a carburetor which is adapted to all the conditions which arise in practice.

What I claim is—

1. In a float-feed carburetor, a chamber or casing having a cavity therein, a guiding-sleeve adjustably arranged within the walls of said cavity, a plurality of ports or openings in said guiding-sleeve, a valve having a plurality of ports arranged to successively register with said first-named ports when the valve is opened, a diaphragm having a tubular extension, a supply pipe or nozzle within said extension, and means for moving the

valve into seating relation upon said dia- 30 phragm.

2. In a float-feed carburetor, a chamber or casing having a cavity therein, a guiding-sleeve adjustably arranged within the walls of said casing, a plurality of ports or openings of different sizes in said guiding-sleeve, said ports or openings being arranged in different angular relations, a valve having ports arranged to successively register with said first-named ports when the valve is opened, 40 and means for admitting a small quantity of carbureted air to the engine when the valve is closed.

3. In a float-feed carburetor, a chamber or casing having a threaded guiding-sleeve projecting therefrom, ports within said guiding-sleeve arranged at different angular positions, a valve having ports adapted to successively register with said first-named ports, and additional means whereby said valve admits carbureted air to the engine. 45

In witness whereof I subscribe my signature in the presence of two witnesses.

GUSTAVE E. FRANQUIST.
